UNITED STATES PATENT OFFICE.

EDGAR D. JOHNSON, OF EAST ORANGE, NEW JERSEY, ASSIGNOR TO WESTERN ELECTRIC COMPANY, INCORPORATED, OF NEW YORK, N. Y., A CORPORATION OF NEW YORK.

REPEATER CIRCUITS.

Application filed February 1, 1918. Serial No. 214,965.

To all whom it may concern:

Be it known that I, EDGAR D. JOHNSON, a citizen of the United States, residing at East Orange, in the county of Essex, State of New Jersey, have invented certain new and useful Improvements in Repeater Circuits, of which the following is a full, clear, concise, and exact description.

The invention relates to repeater circuits wherein a two-way transmission of currents, such as telephone current or ringing current, is provided.

As shown in the application of Nicolson, Serial No. 223,221, filed March 18, 1918, for repeating systems, there is provided a repeater circuit wherein it is possible to dispense with switches for reversing the repeating circuits, one of two oppositely connected repeater circuits being rendered inoperative in response to current impressed on the line to permit the transmission of current through the other repeater branch only.

The above Nicolson application makes use of vacuum tube repeaters of the audion type and provides two repeater paths in parallel and amplifying currents in opposite directions. Each line section is adapted to receive current from one of the repeater paths for transmission in one direction, and is adapted to transmit current to the other path for transmission in the other direction. In order that there shall be no local circulation of power at the repeater station, it is necessary that the line sections, when receiving current from one repeater path, shall send the amplifying current out upon the line without also sending the amplified current to the other repeater path.

This is accomplished according to the present invention by supplying the current from each repeater path to the other, but in phase opposition to the current supplied from one repeater by way of the line section to the other repeater. The opposed currents produce a resultant zero effect in one of the repeater paths, and in this way current delivered by either repeater serves to render the other inoperative, so that the amplified currents delivered by one repeater are sent exclusively out upon the line, no amplified currents being transmitted back through the other repeater circuit to produce an objectionable local circulation of power through the repeater circuits.

The invention will be described in further detail in connection with the drawings, in which Fig. 1 illustrates a two-way repeater circuit in which an auxiliary electrode with in a vacuum tube is energized at times to render a portion of the circuit inoperative; Fig. 2 illustrates a circuit similar to that in Fig. 1, except that no auxiliary electrode is provided, the currents having a modified phase being supplied to the ordinary input electrode of a vacuum tube; and Fig. 3 illustrates the preferred form of the invention where the phase shift is accomplished by repeating coils.

In Fig. 1, between the lines 1 and 2, is provided a repeater path 3 for transmitting current in a direction from line 1 to line 2, and a repeater path 4 for transmitting currents in the opposite direction. The repeater path 3 comprises a vacuum tube amplifier 5 of the audion type which is provided with an auxiliary electrode 6. Coupled to the output circuit of the amplifier 5 is the potentiometer 7, through which potential is supplied to the amplifier 8 of the audion type, which supplies amplified currents to the line 2.

In order that repeater 11 may be rendered inoperative while repeater 8 delivers current to line 2, the potentiometer 7 also supplies potential to the amplifier 9 of the audion type. Furthermore, the circuit 4, leading from potentiometer 7 to repeater 11 by way of repeater 8 and line 2, is simulated by the circuit from potentiometer 7 to repeater 11 by way of repeater 9 and circuit 13. The neutralizing currents, delivered to repeater 11 over the neutralizing circuit including repeater 9, will be of the same wave form as the currents fed back to repeater 11 from 2.

In order that the neutralizing circuit may simulate the load circuit, the repeater 9 and the repeating coil 12 coupling the output circuit of repeater 9 to the input circuit of repeater 10 are similar respectively to the repeater 8 and repeating coil 14 coupling repeater 8 to the line 2. Furthermore, the net work 15 which is here shown as comprising a resistance and a condenser is similar to the impedance of the line 2, and the repeating coil 16 coupling the circuit 13 to the tube 11 is similar to the repeating coil 17 coupling the line 2 to the repeater 11.

By means of the potentiometer 7, the potential supplied to the tubes 8 and 9 may

be adjusted so that the amplitude of the current supplied by the repeating coil 16 to the auxiliary electrode 10 is the same as the amplitude of the current delivered to the tube 11 through the repeating coil 17. The phase of the current delivered by the neutralizing circuit to repeater 11 may be made opposite to the phase of the current delivered to repeater 11 by line 2, by reversing the connections of repeating coil 16, for instance. The potential supplied to the auxiliary electrode 10 being of the same wave form, equal in amplitude, and opposite in phase to the current delivered by the line 2 to the input side of the amplifier 11, the electron stream within the tube 11 is equally and oppositely affected so that no current is transmitted back through the path 4 from line 2, but is sent out upon line 2 in the desired manner.

For transmission of current from the line 2 to the line 1, currents originating in the line 2 cannot pass back through the path 3, since the tube 8 is essentially a unilateral conductor. Currents impressed on the line 2, are, however, amplified by the tube 11 to its output circuit to which are coupled circuits similar to those described in connection with repeater path 3, the repeater 5 being rendered inoperative, the amplified currents going out upon the line 1.

The circuits shown in Fig. 2 are the same as those of Fig. 1, except that the currents delivered by repeating coils 16 and 17 are delivered to the same and usual input electrode 19 of a tube 20, which corresponds to the repeater 11 of Fig. 1.

Fig. 3 illustrates the preferred circuit. This is similar to the other figures and particularly to Fig. 1, except as to the neutralizing circuit for changing the phase of the currents to be supplied to repeater 11 (Fig. 3) to render the same inoperative when transmitting in a direction from line 1 to line 2.

The circuit from the points AB to repeater 11 by way of repeater 8 and coils 14 and 17 is the same as shown in Fig. 1. The currents taking this path are subjected to the following phase changes: Assume the currents at points AB to have zero degrees phase then the potential induced in the secondary of repeating coil 21 is 90° behind the current in the primary. The tube 8 introduces no phase change, the current in its output circuit being in phase with the input potential. The current in the output circuit of tube 8 is 90° behind the current at points AB. In the secondary of coil 14 there will be induced a potential 90° behind the current in the output circuit of tube 8 and 180° behind the current at points AB. The current delivered by the secondary of coil 14 to the line 2, will be substantially in phase with its driving potential

if the resistance of the line 2 is large as compared to its impedance. Even though the resistance of the line 2 is not large, resulting in a phase shift of the current in line 2 with respect to the potential across the secondary of coil 14, this may be compensated for in the neutralizing circuit 22. The current in line 2 induces a potential in the secondary of coil 17 lagging 90° behind the current in line 2, this potential being applied to the repeater 11 and being 270° behind the phase of the current at points AB.

The phase shift of the currents in the neutralizing circuit 22 is as follows: By means of the resistance 23 the amplitude of the potential applied to the electrode 10 may be regulated. The current in the primary of coil 24 induces a potential in the secondary lagging by 90° the current in the primary. This potential produces a current in circuit 25 which lags this induced potential by 90° since circuit 25 is highly inductive as shown. The 180° phase shift is increased to 270° by the repeating coil 26. A lag of 270° is also experienced by the potential applied to tube 11 from line 2. The potential applied to electrode 10 may be reversed in phase, however, by reversing the connections of any one of the coils in the circuit 22. If, however, the exact phase lag through coils 21, 14 and 17 is different from 270° as described above, it is evident that the apparatus in neutralizing circuit 22 should be adjusted until it produces a phase lag of the same value, thereby producing the desired neutralization. It is to be understood that this invention is not limited to the particular arrangement described for producing the phase lag in the neutralizing circuit, since, as is shown in the art, a phase shift may be produced by various networks of which the one described is only one type.

The circuit in Fig. 3 is simpler than that shown in Figs. 1 and 2, no repeater such as 9 in Fig. 1 being employed. The neutralizing potential may be applied to the usual input electrode of the repeater as in Fig. 2.

While the invention is of particular advantage for the two-way transmission of telephone currents, it is not limited to this use but may be employed as a repeater in any circuit.

What is claimed is:

1. The combination of a line, a vacuum tube repeater having its output circuit effectively connected to transmit current to said line, and means responsive to a current impressed on said line for supplying two currents of substantially equal amplitudes and opposite phases to said repeater.

2. The combination of a line, a vacuum tube device having an input circuit and having an output circuit effectively connected to transmit current to said line, and means re-

sponsive to a current impressed on said line for supplying two currents of substantially equal amplitudes and opposite phases to said input circuit.

5. A two-way repeater system comprising a line, repeaters of the audion type connected in opposition in said line, and means responsive to current impressed on said line for impressing waves of substantially equal amplitudes and opposite phases on one of said repeaters.

10. 4. The combination of two lines, two repeaters of the audion type, the output circuit of one of said repeaters and the input circuit of the other of said repeaters being connected to said lines and a connection between said repeaters independent of said lines, said connection supplying current of substantially the same wave form as that to be repeated.

15. 5. The combination of a line, two repeaters of the audion type, the output circuit of one of said repeaters and the input circuit of the other of said repeaters being connected to said line, and a connection between said repeaters, said connection comprising means for supplying waves having a modified phase.

20. 6. A two-way repeater system comprising two lines, repeaters of the audion type connected therebetween, and a plurality of phase changing circuits connecting said repeaters,

one of said repeaters being pointed for transmission therethrough in one direction between said lines, and the other repeater being pointed for transmission therethrough in the opposite direction between said lines.

25. 7. A line, a repeater having an electron stream and having an output circuit effectively connected to transmit current to said line, and means including two circuits energized from said line for similarly but oppositely controlling said stream for successive waves.

40. 8. A two-way repeating system comprising two lines, two oppositely connected repeater paths therebetween, and neutralizing circuits comprising amplifiers interconnecting said repeaters, said circuits supplying currents of substantially the same wave form 45 as the current to be repeated.

45. 9. A line, a repeater having means for producing an electron stream, and means including two circuits energized from said line for similarly but oppositely controlling said stream by a plurality of currents of alternating character and of substantially the same frequency, said repeater having its output circuit effectively connected to transmit current to said line.

50. 60. In witness whereof, I hereunto subscribe my name this 18th day of January A. D., 1918.

EDGAR D. JOHNSON.
